AUTOCLAVABLE PICK-GUARD

Raymond H. Haerr, Cincinnati, Ohio, assignor to
Xomox Corporation

Filed Nov. 8, 1974, Ser. No. 522,199

Term of patent 14 years

Int. Cl. D24—02; D8—08

U.S. Cl. D32—1 R

FIG-1

FIG-2

FIG-3

FIG-4

FIG-5

FIG-6

FIG-7

FIG-8

FIG. 1 is a top perspective view of the top, end and side of an autoclavable pick-guard, showing my new design.

FIG. 2 is a perspective view of the bottom, opposite end, opposite side thereof.

FIG. 3 is a plan view of the right side of FIG. 1.

FIG. 4 is a plan view of the right end of FIG. 3.

FIG. 5 is a plan view of the top of FIG. 3.

FIG. 6 is a plan view of the left end of FIG. 3.

FIG. 7 is a bottom plan view of FIG. 3.

FIG. 8 is a perspective view of FIG. 3 in a fully opened position.

I claim:

The ornamental design for an autoclavable pick-guard, as shown.
